UNITED STATES PATENT OFFICE.

FERDINAND J. TILLMAN, OF ST. LOUIS, MISSOURI.

CIPHER-PRINTING MECHANISM.

1,301,986.

Specification of Letters Patent. Patented Apr. 29, 1919.

Application filed August 13, 1917. Serial No. 185,813.

To all whom it may concern:

Be it known that I, FERDINAND J. TILLMAN, a citizen of the United States of America, and a resident of the city of St. Louis and State of Missouri, have invented 5 certain new and useful Improvements in Cipher-Printing Mechanism, of which the following is a specification.

The primary object of this invention is 10 to provide an improved printing mechanism relative to writing machines, that will print a series of ciphers with one actuation of an operating key.

Another object is to provide an improved 15 automatic cipher printing mechanism that can readily be attached to the adapted mechanisms of a writing machine.

A further object is to provide an automatic printing mechanism that is carried 20 by a type carrying bar of a writing machine.

Other and further objects will appear in 25 the specification and be specifically pointed out in the appended claims, reference being had to the accompanying drawings exemplifying the invention, and in which,

Figure 1 is a longitudinal sectional view 30 showing a portion of a typewriting machine, and having this improved cipher printing mechanism applied thereto.

Fig. 2 is a fragmentary front elevation, partly in section of Fig. 1.

Fig. 3 is a fragmentary horizontal section taken on the line III—III of Fig. 1.

Fig. 4 is an enlarged end view of the 35 type carrying bar with this improved cipher printing mechanism attached.

Fig. 5 is a fragmentary plan view of Fig. 4.

Fig. 6 is a fragmentary plan view of a 40 portion of a platen roller, showing this improved cipher printing mechanism in operative relation thereto.

Fig. 7 is a fragmentary view, partly in 45 section, taken on the line VII—VII of Fig. 1.

Referring to the drawings, 1 designates a typewriter frame, 2 the movable carriage mounted on said frame, 3 and 4 platen 50 roller and tabulating rack, respectively, mounted on said carriage.

Swingingly mounted in said frame as designated at 5 are the usual key levers 6 and arranged above said key levers 6 is a row 55 of tabulating key levers 7 which are pivotally mounted at 7' in the frame 1. This

improved cipher printing mechanism in this instance is operably related to one of the key levers 6, and if it is desired to mount this improved mechanism on an already built typewriter, it is thought preferable to elect one of the key levers that is operably related to the uppermost right hand type carrying bar, said key lever and type carrying bar being generally used for the printing of characters which are not very material in typewriting, such as the key lever which is adapted to print the characters "@" and "¢", although it is to be understood that in new typewriter machines and 70 the like, an extra key can be added for the manipulation of this improved cipher printing mechanism.

Referring again to the drawings and to Figs. 1, 2 and 3, the key lever designated 75 as A has been elected for the purpose of disclosing an operative construction relative to actuating this improved cipher mechanism.

Secured to the sill portion 8 of the typewriter frame 1 by a screw 9 is a bracket 10, and pivotally mounted at 11 to said bracket is a bell crank lever 12, the upwardly extending portion 13 of said lever having a right angular bent portion 14 formed thereon, 85 which is in the path of downward travel of the lever actuating portion 15 of the key lever A.

Pivotedly secured to said lever portion 15 as designated at 16 is an upwardly extending pull rod 17, said rod being secured at its opposite end at 18 to the extending lip 19 of the type carrying bar 20, said bar being pivotally secured at 21 to the type bar support 22.

Instead of the usual type being carried at one end of the type bar 20, this improved cipher printing mechanism is mounted in lieu thereof, and comprises a revolvably mounted roller 23, mounted on an axis 24, 100 said axis being secured to one end of the type bar 20, and carried by said roller 23 are a plurality of cipher characters 25.

In rolling contact with the cipher characters of said roller 23 is a revolvably mounted inking roller 26, mounted on an axis 27, said axis being secured to the type bar 20 adjacent the roller 23.

Pivotedly secured at 28 to the depending portion 29 of the bell crank lever 12 is a rod 30, the opposite end of said rod being secured at 31 to a tabulating key bar 32, there

being a plurality of said bars 32, each bar 32 being pivotally secured at one end to its respective tabulating key lever 7, each of said bars 32 at their opposite ends being secured to a tabulating stop pawl 33, each of said stop pawls being pivotally mounted as designated at 34, and formed on the upper end of each stop pawl is an engaging portion 35.

10 Operably related to said stop pawls 33 is a carriage releasing bar 36 having a pivotally mounted upwardly extending portion 37 which is pivoted at 37^a and is operably related to the mechanism, not shown, for allowing the carriage to travel freely to the next tabulating stop in order.

Referring to the tabulating keys 7 which relate to the mechanisms pertaining to the finding of columns relative to entering different amounts which is a known quantity as regards the listing of items in column formation, this improved cipher printing mechanism is operably related therewith, and for the purpose of more clearly illustrating the operation of this cipher mechanism, the tabulating key bearing number one-thousand and designated on the drawing as B, and bar 32 and stop pawl 33 relating thereto being further designated in the drawing as B¹ and B², respectively, being elected as co-operable with the rod 30 of the bell crank lever 12.

In the operation of this improved cipher printing mechanism, assuming it is desired 35 to enter the amount of one-thousand dollars on the sheet which is mounted over the platen roller 3 on which the different amounts are to be entered in a column, the column finder or stop 38 is placed on the rack bar 4, and located in order with the decimal tabulating key.

The limiting stop is then properly located on the rack bar 4 at a distance away from the stop 38 with respect to the number of 45 characters relative to writing one-thousand, then the one-thousand tabulating key B is operated, and bar B¹ connected thereto is moved rearwardly, thereby causing the lower end of stop pawl B² to be moved rearwardly, and incidentally swinging the engaging portion 35 of said stop pawl B² forwardly and in the path of travel of the column finder stop 38.

When the lower end of the stop pawl B² 55 was moved rearwardly, the releasing bar 36 was engaged by said stop pawl and the extending portion 37 of said releasing bar was simultaneously disengaged from engagement with the carriage 2, thereby allowing 60 the carriage to travel in the usual manner until the stop 38 engages the forwardly extending portion 35 of said stop pawl B², thereby stopping and holding the carriage 2 against further travel, the carriage and 65 sheet mounted thereon then being in a posi-

tion to receive the entry of one-thousand dollars.

The key lever 6 bearing character "1" is then operated, thereby causing figure one to be printed on the sheet, then the key designated as A in the drawings and being operable with the type bar 20 carrying this improved ciphering device is operated, the roller 23 thereof bearing against the sheet and platen roller 3, the operator holding 75 said key designated as A down, and incidental therewith the bell crank 12 is operated and held down, thereby pushing rod 30 and bar B¹, and moving the engaging portion 35 of the stop pawl B² forwardly, 80 and in position to engage the limiting stop 39 on rack bar 4 and next in order.

Incidental with the moving of the lower portion of the stop pawl B² rearwardly in the last mentioned operation, the carriage 85 releasing member 36 was also moved, thereby allowing the carriage to move, and inasmuch as the cipher character roller 23 is engaged against the platen roller 3, said platen roller will cause said cipher carrying roller 90 to turn, thereby printing a series of five cipher characters after the already imprinted character one, the limiting stop 39 eventually engaging the engaging portion 35 of the pawl B² and stopping the carriage from 95 moving immediately after five cipher characters have been printed.

From the aforesaid, it is to be seen after the column position has been found, two operations only will be required in order to 100 establish the amount of one thousand as relating to dollars and no cents (\$1000.00), the two operations being the manipulation of the key relating to the character one and the manipulation of the key related to the 105 cipher printing mechanisms. In order to provide a space or line between the dollars and cents in a column, a spacer member 40 is slidably mounted on a guide rod 41, said rod being located behind the front scale 42, 110 said front scale bearing indicating marks corresponding to the indicating marks on the top of the rack bar 4. This spacer member is mounted in position or registration with the decimal column, and incidentally 115 coinciding with the position of column finder stop 38, the sheet of paper when mounted on the platen roller 3 being mounted between said spacer member and said roller. Therefore, assuming that when the cipher carrying roller 23 has been operated and brought to bear against the sheet mounted on the platen roller 3, said cipher roller will impress or imprint three ciphers before said 120 roller comes in contact with the spacer member 40, said member preventing the roller from printing on the sheet, said roller after riding over said spacer member printing the two ciphers denoting no cents.

Assuming it is desired to enter the amount 125

of two hundred twenty dollars and no cents, in this case the tabulating key bearing 100 for denoting the position relative to the hundreds column is operated, then the key 5 lever representing numeral two will be operated twice, after which the key A representing the automatic cipher printer will be operated, thereby printing the three ciphers required as denoting two hundred twenty 10 dollars and no cents (\$220 00).

For preventing the printing roller 23 from revolving by momentum after the same has been operated by the platen roller 3, and for holding said roller 23 in a set position 15 relative to proper printing of the ciphers carried thereby, a notched wheel 43 is mounted on said roller 23, there being a notch relating to each cipher and for engagement with said notches is a retarding 20 leaf spring 44, one end of which is secured to the type bar 20, as clearly shown in Fig. 5.

What I claim is:

1. In combination, an operating key, a typing bar coöperable with said key, a printing device carried by said bar for printing a plurality of characters during one operation of said key, a tabulating stop pawl coöperable with said key, and a movable member for causing said printing device to omit 30 the printing of one of its characters.

2. In a writing machine, a digit bearing member tabulating stop pawl and a cipher bearing member, means for operating said members and said stop pawl, said cipher 35 bearing member adapted to imprint a plurality of ciphers with one operation thereof after said digit bearing member has been operated on, said stop pawl when operated providing means for stopping the printing 40 of said cipher bearing member after said cipher bearing member has been operated.

3. In combination, an operating key, a type carrying bar related to said key, a revolvably mounted type carrying member located at one end of said bar, a spacer member for engagement with said type carrying member and a tabulating stop pawl coöperable with said key.

4. In combination, an operating key, a 50 type carrying bar related to said key, a revolvably mounted type carrying member located at one end of said bar, a tabulating stop pawl coöperable with said key, a spacer member coöperable with said type carrying

member, and a movable carriage coöperable 55 with said type carrying member and said stop pawl.

5. In combination, an operating key, a type carrying bar related to said key, a revolvably mounted type carrying member 60 located at one end of said bar, a tabulating stop pawl coöperable with said key, a movable carriage coöperable with said stop pawl, a platen roller mounted in said carriage for engagement with said type carrying member and a spacer member to be engaged by said type carrying member.

6. A type carrying bar, a movably mounted type carrying member carried by said bar adapted to print a series of characters with 70 one operation of said bar, means for actuating said bar, a stop pawl adapted to simultaneous movement with said bar, and a spacer member coöperable with said type member.

7. The combination of a platen roller, a printing member actuated by said roller, a guiding member parallelling said roller, a stop pawl coöperable with said printing member, and a spacer member movably 80 mounted on said guiding member, said printing member when operated on by said roller adapted to print a series of characters, said spacer member providing means for preventing said roller from printing one of 85 its characters.

8. In a writing machine, a plurality of character printing members, a cipher printing member when actuated adapted to print a plurality of ciphers, a tabulating stop 90 pawl coöperable with said cipher member, and a spacer member coöperable with said cipher member for preventing said cipher member from printing while said cipher member is being actuated.

9. In a writing machine, a type carrying bar bearing a digit character, a second type carrying bar bearing a cipher printing member, an operating key for each of said bars, said second mentioned bar when operated 100 by its respective key causing the cipher printing member carried thereby to imprint a plurality of ciphers during one actuation of said key after said digit bearing bar has been operated on and a stopping mechanism 105 for limiting the extent of printing of said cipher printing member.

FERDINAND J. TILLMAN.
